UNITED STATES PATENT OFFICE.

LOUIS V. ZIEGLER, OF RIDGEFIELD PARK, NEW JERSEY.

SEPARATOR FOR GAS-STOVES.

1,344,670.

Specification of Letters Patent. Patented June 29, 1920.

Application filed July 1, 1919. Serial No. 307,930.

To all whom it may concern:

Be it known that I, LOUIS V. ZIEGLER, a citizen of the United States, residing at 97 Highland Place, Ridgefield Park, in the 5 county of Bergen, State of New Jersey, have invented certain new and useful Improvements in Separators for Gas-Stoves; and I do hereby declare the following to be a full, clear, and exact description of the 10 invention, such as will enable others skilled in the art to which it appertains to make and use the same.

This invention relates to an attachment for gas stoves and the like having for its 15 object the elimination of greasy vapors escaping through the outlet flue from the oven.

Commercial gas stoves are commonly provided with an outlet flue connected to the 20 oven to carry off the products of combustion and the greasy vapors resulting from culinary operations. This flue may be connected to a chimney by a suitable pipe, but more frequently no chimney or other outlet 25 let from the kitchen is available, and in common experience, the stove flue discharges directly into the kitchen. The greasy vapors resulting from broiling and roasting operations in the oven, mix with 30 the combustion products escaping from the burners. The vapors remain in suspension, however, only while the gases are sufficiently heated and are readily deposited upon contact with a relatively cooler surface. It is 35 usual, therefore, to find a greasy discoloration on the wall behind the outlet flue, which, because of the character of the deposited material, is removed with difficulty and is accordingly frequently allowed to 40 remain on the wall. The grease holds dust particles which come in contact therewith, and the result is an unsightly and unsanitary condition.

It is the purpose of the present invention 45 to provide a relatively simple and inexpensive device which will successfully separate the greasy vapor from the combustion gases without affecting the efficiency of the oven, thus preventing the deposit above referred 50 to, lightening the housewife's labors and insuring a more sanitary condition of the kitchen.

Further objects and advantages of the 55 invention will be apparent as it is better understood by reference to the following

specification when used in connection with the accompanying drawing illustrating the preferred embodiment thereof, in which,

Figure 1 is a view in perspective of a 60 gas stove with my device applied thereto; Fig. 2 is a vertical section through one form of my invention;

Fig. 3 is a section on the line 3-3 of Fig. 2;

Fig. 4 is a vertical section through an 65 other and slightly different form of my invention; and

Fig. 5 is a section on the line 5-5 of Fig. 4.

In Figs. 2 and 3 of the drawings I have 70 illustrated a form of my invention which has proven to be eminently satisfactory in accomplishing the desired objects. The device comprises a short pipe section 5 which may be of suitable cross-sectional shape and 75 dimensions to closely fit the outlet flue 6 of the stove 4. The pipe section 5 may be of any desired length, this factor being immaterial to the success of the device. Preferably a short section is employed because 80 the appearance of the device is enhanced and it is more readily cleaned.

The free end of the pipe section 5 is closed preferably by a plate 7 secured thereto by a strap 7', and an opening or slot 85 8 is provided in the pipe section forming a restricted outlet through which the gases escape. The plate 7 is preferably provided with a depending lip 9 spaced from and disposed in front of the opening or slot 8 in the 90 pipe section 5. In arranging the device on a gas stove the lip 9 is advantageously disposed so that the gases are discharged away from the wall of the room in which the stove is placed. 95

To insure the separation of the greasy vapor from the gases escaping from the device, I preferably secure a sheet 10 of incombustible fibrous material, such as asbestos, to the inner face of the plate 7 and the 100 sheet may be perforated as at 11 to increase the exposed surface thereof and to provide lodgment for the greasy particles. The sheet 10 is preferably supported in the device so that it may be readily removed for replacement when necessary.

In Figs. 4 and 5, I have illustrated a slightly different form of my device which is in every respect similar to the form previously described except for the arrange- 110

ment of the fibrous material. In the latter form of my device, I provide two sheets or baffles of fibrous material 12 and 13 suitably secured to a rectangular frame 14 which 5 may be constructed of strap-iron, in such a manner that the resiliency of the side members 15 thereof causes the frame to be held in adjusted position within the pipe section 5. The frame 14 is, however, readily 10 movable to permit cleaning of the device. Both of the sheets 12 and 13 of fibrous material are provided with perforations 16, the 15 perforations in the lower sheet 13 permitting the passage of gases therethrough and those in the sheet 12 providing lodgment for the greasy particles as hereinbefore described.

The operation of the device which forms 20 a cover for the gas stove flue will be readily understood from the foregoing description. The gases carrying greasy vapor from the oven escape from the flue to the cover in which their velocity is reduced as they impinge against the asbestos sheet or sheets. 25 The vapors are separated and the gases are deflected through the opening or slot 8 against the lip 9. The gases are again deflected by the lip and are dissipated in the atmosphere, substantially free from greasy vapors. The device, moreover, by regulating 30 the escape of gases from the stove, insures a more even temperature in the oven and thus increases the utility of the stove. Cleaning is readily accomplished by removing 35 the device from the stove and withdrawing the asbestos sheets which may be replaced or new sheets may be inserted.

The device is small in size and adds to the appearance of the stove by covering the 40 unsightly flue outlet. It is of inexpensive construction throughout and is obviously capable of advantageous employment for its intended purpose.

Various changes may be made in the 45 form, arrangement and construction of the parts without departing from the invention or sacrificing any of the material advantages thereof.

I claim:

1. A device for separating greasy vapors 50 from gases escaping through a gas stove flue, comprising a tubular cover adapted to be applied to the flue of a gas stove and having an imperforate top, grease absorbent material positioned at the under side of said 55 top, and said cover having an outlet so disposed with respect to said material that the gases are deflected through the outlet by impingement on the surface of said material.

2. A device for separating greasy vapors 60 from gases escaping through a gas stove flue, comprising a tubular cover adapted to be applied to the flue of a gas stove, and having an imperforate top, grease absorbent material positioned at the under side of said 65 top, said cover having an outlet so disposed with respect to said material that the gases are deflected through the outlet by impingement on the surface of said material, and a lip depending in front of said outlet to 70 again deflect the gases as they pass therethrough.

3. A device for separating greasy vapors from gases escaping through a gas stove 75 flue, comprising a tubular cover adapted to be applied to the flue of the gas stove, and having an imperforate top, a transversely disposed removable sheet of grease absorbent material arranged within said cover below said top and in the path of said gases, 80 said cover having an outlet for the gases below the plane of said sheet through which the gases are deflected by impingement on said sheet.

4. A device for separating greasy vapors 85 from gases escaping through a gas stove flue, including a cover for said flue, a plurality of baffles arranged in the path of said gases within said cover, and a restricted outlet for said gases below the plane of the 90 uppermost baffle and laterally disposed with respect to said baffles, through which said gases are deflected by impingement on the uppermost baffle.

In testimony whereof I affix my signature. 95
LOUIS V. ZIEGLER.
